UNITED STATES PATENT OFFICE.

CHARLES R. CAMERON, OF LOS ANGELES, CALIFORNIA.

INDICATING MEANS.

Application filed August 29, 1922. Serial No. 585,090.

To all whom it may concern:

Be it known that I, CHARLES R. CAMERON, a subject of the King of Great Britain, and residing at Los Angeles, in the county of 5 Los Angeles and State of California, have invented new and useful Improvements in Indicating Means, of which the following is a specification.

This invention relates to indicating means 10 which may be utilized for various purposes, such as determining from a direction rearwardly of a head light whether or not said head light is burning. The device may be utilized in conjunction with railway switch 15 lanterns and the like, or it may be utilized in conjunction with motor vehicles. The device in particular will indicate the exact condition of the light, as well as whether or not the same is burning.

20 In practicing the invention I provide a device which includes a casing having a light or vision-transmitting part and a receiving part, whereby the general appearance of a lamp within a head light or other device 25 may be viewed as to its general appearance at the receiving part, and in addition the intensity of its burning may likewise be determined.

With the above and other objects in view, 30 the invention consists in the novel and useful provision, formation, construction and relative arrangement of the parts, members and features as disclosed in the drawing, described in the following statement and 35 finally pointed out in claim.

In the drawing:

Figure 1 is a cross sectional view of a head light incorporating the indicating means;

40 Figure 2 is a view similar to Figure 1, showing a modified form of indicating means; and

Figure 3 is a perspective view of the indicating means shown in Figure 1.

45 Corresponding parts in all the figures are designated by the same reference characters.

Referring with particularity to the drawing, A designates in its entirety the indicating means of Figures 1 and 3, and B the indicating means shown in Figure 2, which indicating means, either A or B, is utilized in the embodiment shown in combination with a head light C, which head light may include the usual outer casing 1 formed with a part 2 adapted to receive a retaining ring 55 3 adapted to hold a lens 4 to said casing 1,

with a reflector 5 within said casing 1 and a source of light 6 normally placed at the focal point of said reflector. It is intended that the device A or B should receive a certain portion of the light rays emitted by the lamp 6 and transmit a reflection of said rays in a direction rearwardly of the head light casing 1. If the head light is used on a motor vehicle it may be easily determined by the driver of the vehicle whether or not the lamp 6 is burning, and likewise to observe the lamp 6 in the case of the device shown by A. The devices A and B are in reality attachments which may be fitted to any form of lantern or the like. The indicating means 60 A may include a casing *a* of three parts, 7, 8 and 9, the parts 7 and 9 being angularly disposed with relation to the part 8. In the showing the casing *a* is rectangular in cross section. The part 7 flares outwardly as 65 shown at 10, and is adapted to receive and maintain in position a translucent member 11, said translucent member closing the mouth of the part 7, as shown at 12. The flared part 10 is provided with a flange 13, 70 which maintains the translucent member 11 in position. In particular the translucent member 11 may be curved, as shown in Figure 3, so as to give a wide field of vision. The mouth 14 of the part 9 is open and any 75 light rays passing through the mouth 14 into the part 9 will be reflected by means of a small reflector 15 set at an angle as between the parts 8 and 9, to a second reflector 16 set at an angle with relation to the parts 7 80 and 8, and from thence the reflector projects the light rays to the translucent member 11. If desired the translucent member 11 may be formed of ground glass, and hence the lamp 6 would appear in miniature upon said 85 ground glass, and its general appearance readily determined. By curving the translucent member 11 it is possible to view the lamp 6, as well as determine whether or not it is burning, from numerous positions; it 90 not being necessary to observe said translucent member from one position. The casing *a* may be provided with a clip member *b* which will cooperate with the ring 3 and the casing 1 for holding the casing *a* in 95 position. In particular, the clip *b* includes a part as 17 joined with the part 8 of the casing *a* with an extended part 18 having its end bent in the form of a letter S forming the parts 19 and 20. In assembling the in-

100 105 110

dicating means A to the head light C, the retaining ring 3 is removed, whereupon the part 2 of the casing 1 is received between the members 19 and 20 of the clip b and the retaining ring then slipped between the parts 18 and 19 of the clip b and the retaining ring 3 then placed upon the member 2 of the casing 1. This will securely hold the indicating means A in position. The part 8 of the indicating means is of sufficient length that the light transmitting part is in contact with the lens 4, as best illustrated in Figure 1, and with the light receiving part above the casing.

15 The modification shown in Figure 2 consists in providing a casing c having the clip member b joined thereto, with said casing c closed at its upper end, as 21, and open at its lower end, as shown at 22, there being an opening 23 in a portion of said casing, with a light receiving member 24 which may be formed of glass or other translucent substance within said casing. One end of said light-receiving member, as 25, projects below the open mouth of the casing, while the other end may be formed with a bead 26 projecting through the opening 23 in the casing. As stated, this device is held in position upon the head light in a similar manner to that just described for the indicating means A. This latter device B will function similar to the device A, with the exception

that the device B will not visualize the lamp 6, but simply absorb light from the said lamp and glow.

35

It is obvious that the clip member b might be bent in a variety of forms and shapes to adapt the same for use and service with various devices, and that the said indicating means may be changed in various respects 40 in departure from the showing, without departing from the true spirit of the invention and the scope of the appended claim.

40

Having thus disclosed my invention, I claim and desire to secure by Letters Patent: 45

The combination, with a head light having the usual casing, lens member, retaining ring for holding the lens to the casing, and lamp within said head light, of means adapted for placement in front of the lens member 50 for receiving rays of light from the lamp and projecting a portion of said rays in a direction rearwardly of the head light; said means being provided with a member adapted to be locked between the casing and retaining ring for maintaining said means in position relative to the head light.

55

In testimony whereof, I have signed my name to this specification in the presence of two subscribing witnesses.

CHARLES R. CAMERON.
